ABSTRACT OF THE DISCLOSURE

A milling machine has a main column provided with a vertical guideway on its front face and a spindle stock at its top. A knee supporting a work table moves vertically on the guideway on the main column. In front of the knee and spaced forwardly from the main column is a vertically extending stationary bracing structure having a vertical guideway on its rear face engaged with a vertical guide part on the front face of the knee, to give added stability to the knee. Handwheels are mounted on the front of the vertical bracing structure, for performing various adjustments such as the vertical adjustment of the knee and the horizontal adjustment of the spindle stock, these handwheels remaining always at a predetermined convenient elevation notwithstanding upward and downward movements of the knee and work table. A counterstay for a spindle head has a supporting post which is supported from the vertical bracing structure and which can be dropped down at least partly into a socket in the vertical bracing structure when it is not in use.

This invention relates to a milling machine, and more particularly to a milling machine of the type in which the work table is supported from a vertically adjustable bracket member of the kind often called a knee.

An object of the invention is the provision of a generally improved and more satisfactory milling machine of this kind.

Another object is the provision of a milling machine having simple and satisfactory means for increasing the rigidity of the knee and therefore of the work table carried by the knee.

Still another object is the provision, in a milling machine of the knee type, of rigid means serving the double purpose of promoting rigidity in the knee at any desired vertically adjusted position thereof, and at the same time furnishing a support for handwheels or other controls which can remain at a fixed elevation at the height most convenient to the operator, regardless of the upward and downward movements of the knee.

A further object is the provision of a box-like stationary member at the front of the knee, which serves the purpose of adding stability to the knee, and at the same time anchoring a counterstay support when the counterstay is in use, and containing the support when the counterstay is not in use.

These and other desirable objects may be attained in the manner disclosed as an illustrative embodiment of the invention in the following description and in the accompanying drawings forming a part hereof, in which:

FIG. 1 is a side elevation, somewhat schematic and with parts broken away, of a milling machine in accordance with a preferred embodiment of the invention; and

FIG. 2 is a perspective view of certain portions of the machine shown in FIG. 1.

Referring now to the drawings, the machine of the present invention, in its preferred embodiment, comprises a rigid base 10, and a rigid column 12 rising from the rear portion of the base. On the top of the column 12 is

2

a spindle stock 14 displaceable in a front and rear direction along horizontal guideways 15. The spindle stock contains the usual conventional horizontal spindle, the front end of which is indicated in general at 16. Another horizontal guideway extends along the top of the spindle stock 14, in a direction parallel to the guideway 15, and on this second guideway there is movably mounted, in a front to rear direction, a second spindle stock 18 which carries a spindle head 20 provided with a spindle 21. The spindle head 20 is rotatable in the conventional manner about a horizontal axis, parallel to the above mentioned horizontal guideways and intersecting the axis of the spindle 21. Therefore the spindle 21 is not necessarily always in a vertical position, but may be turned to various angular positions. However, it is quite frequently used in a vertical position and is commonly referred to, in a machine of this general type, as the vertical spindle.

Extending up and down the vertical front face of the column 12 are vertical guideways 22, along which moves vertically a knee 24 which can be raised and lowered by means of the feed screw or feed spindle 26. The knee 24 carries on its top a work table 28 for carrying the work piece which is to be operated upon by tools mounted in either or both of the spindles 16 and 21. The work table 28, carrying the work piece with it, may be displaced in a longitudinal horizontal direction by any conventional feeding means operated, for example, by the handwheel 30.

Near the front of the machine base 10, and rigid therewith, is a box-like structure 32. On its rear vertical face, this structure 32 carries vertical guides 34 which mate with corresponding guide portions at the front of the knee structure 24. On the box 32, preferably on the front face thereof, there are suitable control members or manipulating members such as the handwheels 36 and 38. For example, the handwheel 36 is connected by bevel gears and shafts, as shown schematically in FIG. 1, with a handwheel 36' mounted on the side of the column 12, and with a worm 40 which, by means of a wormwheel 42, drives the vertical feed screw or feed spindle 26 for adjusting the height of the knee 24 and work table 28. Similarly, the handwheel 38 is connected through shafts and bevel gears with a handwheel 38' on the side of the machine column 12, and with conventional feeding means including, for example, the worm 46, wormwheel 48, and screw feed spindle 50 for imparting forward and rearward horizontal movements to the spindle stock 14. Since the control members 36 and 38 are mounted on the stationary box structure 32 rather than on the vertically movable knee 24, these control members remain at a constant elevation and such elevation can be designed to be at the most convenient height for the operator. Thus he can easily operate the control members at all times, overcoming the disadvantage experienced in conventional machines of the knee type, where the control members, if carried by the knee, are likely to be uncomfortably low when the knee is in a relatively low position and uncomfortably high when the knee is in a relatively high position.

The box structure 32 may be provided with a vertical socket or opening 51 in which a vertical post or support 52 may be seated when desired. This post 52 serves to support the forward end of a counterstay or brace 54 for the vertical spindle head 20, when it is desired to use such a brace for giving greater rigidity to the spindle head. A suitable clamp (conventional per se) clamps the post 52 in its elevated position when the counterstay is in use, and permits it to be dropped to a position wholly or mainly within the socket 51 when the counterstay is not being used.

With this construction, the rigid box structure 32,

rigidly connected with and preferably integral with the base 10, serves to give added stability to the front of the knee structure 24 in any position thereof through its range of vertical adjustment. It is to be noted especially that such a box-like structure 32, when used in combination with the main vertical guides 22, gives the knee and work table great rigidity against horizontal torsional forces such as frequently encountered during certain types of milling operations. This is a great advantage and improvement over prior milling machines of the type in which the knee is supported entirely from the rear and has no front support, and also over those types of milling machines in which the knee has a column of circular cross section to assist in supporting it near its front end. Such circular columns are found in practice to give very little strength or rigidity against horizontal torsional forces. The massive box-like structure 32 of the present invention, however, having a relatively large area in plan or in horizontal section, gives adequate support against horizontal movement of the front end of the knee, and thus, in combination with the rear guideway 22, holds the knee rigidly against horizontal torsional movements. At the same time, such a massive box-like structure serves admirably as a mounting place for mounting the controls and operating elements such as 36 and 38, which are always at a convenient height as above explained. Also, suitable clamping means (conventional per se) may be used to clamp the front of the knee to the guideway 34 on the box 32, in any adjusted elevation of the knee, when greater stability in a vertical direction is desired.

The present construction is distinguished basically from machine tools in which the work table is not supported on a vertically adjustable knee but, rather, directly on the bed of the machine. In such machines (i.e., machines of the bed type) there is no necessity of additionally supporting and stiffening the support of the table, because the work table is directly on the bed. Also, in such machines it is immaterial whether the parts which carry the control or operating elements are of greater or lesser rigidity. But when dealing with a machine of the knee type (that is, one in which the work table is carried by a vertically adjustable knee) the rigidity of the knee under the displacing forces encountered during the machining operation becomes very important, and the provision of control members at a convenient and constant height also becomes important in order to reduce the fatigue of the operator. The present invention provides a happy solution by mounting the control members at a fixed elevation on a rigid box-like structure which at the same time serves as an additional support or brace for the knee, particularly resisting horizontal displacing forces to which the knee may be subjected.

It is seen from the foregoing disclosure that the objects and purposes of the invention are well fulfilled. It is to be understood that the foregoing disclosure is given by way of illustrative example only, rather than by way of limitation, and that without departing from the invention, the details may be varied within the scope of the appended claims.

What is claimed is:

1. A milling machine of the type comprising a base, a machine column rising from said base and having a vertically extending guideway, a vertically movable knee

projecting forwardly from said guideway and having its rear side guided for upward and downward movement along said guideway, a work table carried by said knee, and a tool spindle mounted on said column and adapted to carry a tool for operating on work carried by said table, characterized by the provision of stationary upstanding rigid means at the front of said knee, said means having a vertical guideway on its rear side for engaging the front side of said knee to give to said knee added stability against displacing forces, feed screw means for moving said knee vertically, a handwheel mounted on the front side of said upstanding means, and shaft and gear means for operatively connecting said handwheel to said feed screw means.

15 2. A milling machine of the type comprising a base, a machine column rising from said base and having a vertically extending guideway, a vertically movable knee projecting forwardly from said guideway and having its rear side guided for upward and downward movement along said guideway, a work table carried by said knee, and a tool spindle mounted on said column and adapted to carry a tool for operating on work carried by said table, characterized by the provision of stationary upstanding rigid means at the front of said knee, said means having a vertical guideway on its rear side for engaging the front side of said knee to give to said knee added stability against displacing forces, feed screw means for moving the position of said tool spindle relative to said machine column, a handwheel mounted on the front side of said upstanding means, and shaft and gear means for operatively connecting said handwheel to said feed screw means.

3. A milling machine of the type comprising a base, a machine column rising from said base and having a vertically extending guideway, a vertically movable knee projecting forwardly from said guideway and having its rear side guided for upward and downward movement along said guideway, a work table carried by said knee, a tool spindle mounted on said column and adapted to carry a tool for operating on work carried by said table, a spindle stock in which said tool spindle is mounted, and a counterstay for bracing said spindle stock, characterized by the provision of stationary upstanding rigid means at the front of said knee, said means having a vertical guideway on its rear side for engaging the front side of said knee to give to said knee added stability against displacing forces, said upstanding rigid means having an opening therein, and a vertical support mounted on said upstanding rigid means for supporting a part of said counterstay, said vertical support being arranged so that it may be lowered into and received at least mainly within said opening when it is not in use for supporting said counterstay.

55 4. A milling machine of the type comprising a base, a machine column rising from said base and having a vertically extending guideway, a vertically movable knee projecting forwardly from said guideway and having its rear side guided for upward and downward movement along said guideway, a work table carried by said knee, a tool spindle mounted on said column and adapted to carry a tool for operating on work carried by said table, a spindle stock in which said tool spindle is mounted, and a counterstay for bracing said spindle stock, characterized by the provision of stationary upstanding rigid means at the front of said knee, said means having a vertical guideway on its rear side for engaging the front side of said knee to give to said knee added stability against displacing forces, said upstanding rigid means having an opening therein, and a vertical support mounted on said upstanding rigid means for supporting a part of said counterstay, said vertical support being arranged so that it may be lowered into and received at least mainly within said opening when it is not in use for supporting said counterstay.
